ABSTRACT OF THE DISCLOSURE

The application discloses a unit for fusing powder images on copy material using conduction of heat through the material. The unit includes a vacuum chest having a thermally conductive wall over which the back of the copy material slides and to which heat is supplied by electrical heaters carried thereon. The walls are provided with spaced openings so that the moving copy material is held in intimate engagement with the wall, and any air film between the wall and the copy material is removed to permit an efficient heat transfer to the powder image by conduction from the wall and through the material.

BACKGROUND OF THE INVENTION

This invention relates to copy making apparatus of the type using fusible powder images and, more particularly, to a new and improved method of and apparatus for fixing or fusing powder images.

Photoelectrostatic machines for making one or more copies of graphic material on sheet or web material form an electrostatic image corresponding to the graphic material which is then placed in visible form by the application of a developer such as a toner material or electroscopic powder. This toner material can be applied in various manners, as by a magnetic brush, cascade techniques, powder cloud generators, or from liquid systems, and is selectively attracted or repelled by the electronic image to provide the visible image. Frequently, the toner material comprises electroscopic particles or powder formed of a thermoplastic resinous material. After the powder or toner image has been formed, it is fixed or placed in permanent form, as by fusion or solvent removal, incident to or after transfer to sheet or web copy material.

One common approach to fixing the powder or particle image relies on the application of heat, and this heat is frequently applied to the image bearing surface using radiation or convection techniques. Since the quantum of heat required for proper fusion tends to be constant for a given thermoplastic toner material, it becomes difficult to attain adequate fixing as the speed at which copies are made is increased without operating the heating units at an undesirably high level or increasing the length of the travel path during which the image is exposed to heat. This increases the size of the machine and introduces the possibility of damaging the copy.

SUMMARY

Accordingly, one object of the present invention is to provide a photoelectrostatic copy machine including new and improved fixing or fusing means.

Another object is to provide an apparatus for fusing powder images that is compact and operable at acceptable temperature levels and is also capable of high speed image fusing.

A further object is to provide a powder image fusing apparatus in which heat is transferred to the image largely by conduction.

A further object is to provide a powder image fusing apparatus including a vacuum chamber having a thermally conductive wall against which the back of the image bearing copy material is held and to which heat for fusing the image is applied.

Another object is to provide a new and improved method of fusing powder images on copy material in which the back of the copy material is held in sliding contact with a heated and thermally conductive member by a pressure differential.

In accordance with these and many other objects, an embodiment of the invention comprises a vacuum chest or chamber having a thermally conductive wall to which are affixed one or more electrical heating elements. The wall is also provided with spaced perforations adjacent the heating elements. The back of a copy sheet containing a powder image is moved over the thermally conductive wall in sliding engagement therewith, and the back of the sheet is held in intimate contact with the thermally conductive wall by the pressure differential communicated to the back of the sheet through the apertures. In this way, heat from the electrical heating elements is transmitted by conduction through the thermally conductive wall and the back of the sheet to fuse the powder image.

Using this method and apparatus, copy material speeds in the range of 15 to 50 feet per minute have been attained using thermoplastic powders having softening points ranging from 70-190° C. It will be appreciated that even greater copy material speeds can be realized by operating the system at the maximum temperature difference between the wall and softening point of the powder. For example, copy material speeds of 65 feet per minute and greater can be realized when using a powder that softens at about 70° C. and maintaining the wall at a temperature of 150° C.

BRIEF DESCRIPTION OF THE DRAWINGS

Many other objects and advantages of the present invention will become apparent from considering the following detailed description in conjunction with the drawings in which:

FIG. 1 is a top elevational view in partial section of a fusing assembly embodying the present invention; and

FIG. 2 is a slightly enlarged sectional view taken along line 2—2 in FIG. 1.

DESCRIPTION OF THE PREFERRED EMBODIMENT

Referring now more specifically to the drawings, there is illustrated a fixing or fusing unit or assembly which is indicated generally as 10 and which is capable of effecting the relatively high speed fusing of powder images carried on web or sheet copy material 12. The powder image can be formed directly on the material 12 or transferred thereto, and in a preferred embodiment is produced on a photoconductive member and transferred to the upwardly facing surface of the material 12 (FIG. 2) by an apparatus of the general type shown and described in detail in the copending application of Loren E. Shelfo, Ser. No. 632,819, filed Apr. 21, 1967, which application is assigned to the same assignee as the present application. The toner powder or particulate material forming the image can be of any of the well known types and in general comprises a pigmented thermoplastic resin having a fusing point in the range between 70-115° C. As the sheet or web material 12 moves through the fusing unit 10, heat is transferred to the powder image by conduction to fuse the powder image and thus place it in permanent form.

The fusing or fixing unit 10 includes a pair of spaced supporting walls 14 and 16 between which is mounted a

vacuum chest or chamber indicated generally as 18. The vacuum chamber 18 is illustrated as being formed of a single sheet of folded metal sealed along an edge 18A and closed at its opposite ends by the side walls 14 and 16 on which it is supported. The wall 14 is provided with an opening 20 by which the interior of the vacuum chamber 18 is coupled to an air moving means or vacuum pump 22 by a section of duct 24. Although the illustrated vacuum chamber 18 is illustrated as being formed of sheet metal, other suitable materials could be used so long as a wall 18B or a suitable portion thereof is formed of a material having good thermal conductivity. The wall 18B is formed with a plurality of rows of openings or apertures 26, 28, and 30 that are spaced from each other in the direction of movement of the sheet or web material 12 relative to the unit 10.

To provide a source of heat for fusing the powder image, the vacuum chest or chamber 18 is provided with electrical heating means including two electrical heating units or assemblies 32 and 34. These two units are generally elongated and are secured to the lower surface of the wall 18B disposed between and extending generally parallel to the rows 26, 28, and 30 of openings or perforations. The heating units 32 and 34 can be of conventional construction including a sole plate brazed or welded to the wall 18B and carrying resistance elements on the opposite surfaces thereof, or can comprise units in which the resistance elements are cast into the sole plates included in the heating units 32 and 34. These units are energized from a suitable source of alternating current energy during periods of use of the copying machine of which the assembly 10 forms a part and preferably are provided with adjustable temperature regulating means of known construction. In one unit 10 constructed in accordance with the present invention, the temperature control means can be regulated to energize the units 32 and 34 to maintain the temperature of the thermally conductive wall 18B at a temperature in the range of 120-150° C.

To provide means for feeding the sheet or web copy material 12 relative to the wall 18B of the vacuum chamber or chest 18, two sets of rollers 36 and 38 mounted on shafts 40 and 42, respectively, are provided. The sets of rollers 36 and 38 are rotated in synchronism so as to advance the material 12 over the heated wall 18B of the vacuum chamber 18 at the desired speed and with the powder image facing outwardly or upwardly away from this wall. In one fusing unit 10 constructed in accordance with the present invention, a variable speed drive (not shown) coupled to the shafts 40 and 42 can be adjusted to advance the material 12 at a speed in a range of 15-50 feet per minute. As illustrated in FIG. 2 of the drawing, the sets of rollers 36 and 38 are offset vertically from each other so that the sheet or web material 12 is held in engagement with the curved and somewhat upwardly inclined wall 18B of the vacuum chest 18.

When the fusing or fixing unit 10 is placed in operation, a control circuit (not shown) associated with the unit 10 or with the copying machine of which the unit 10 is a part is energized to initiate the operation of the vacuum pump or air moving means 22 so that air is withdrawn from the vacuum chamber 18 through the opening 20 and the duct 24. Air is removed by the moving means 22 at a greater rate than air can enter through the rows of openings 26, 28, and 30 so that a pressure differential is maintained across the wall 18B. The energization of the control circuit also initiates the energization of the electrical heating units 32 and 34 so that the thermally conductive wall 18B or the thermally conductive portion thereof is heated to the desired temperature under the control of the temperature regulating means. This temperature can be adjusted in accordance with the type of toner material to be fused by the unit 10. If desired, the control circuit for the electrical heating units 32 and 34 can be provided with a control which maintains the

wall 18B at a temperature somewhat lower than that required for proper fusing during standby periods and is elevated to the proper fusing temperature when the unit 10 is actually placed in use to fix copies.

Powdered images are then produced on the copy material 12 either directly or, in the preferred embodiment, by transfer to the material 12 in a machine of the type described in the above-identified copending application of Shelfo et al. In this embodiment, the copy material 12 preferably comprises plain or untreated paper, and the material 12 is fed to the nip between the inlet rollers 36 with the powder image facing upwardly (FIG. 2) or away from the wall 18B. The rollers 36 which were placed in operation together with the rollers 38 when the unit 10 was placed in operation feed the leading edge of the copy material 12 against the upwardly inclined wall 18B and advance the leading edge over the wall 18B to be received within the nip between the rollers 38, which in turn feed the copy material to a discharge point.

As the copy material 12 moves over the wall 18B, it closes off communication between the atmosphere and the interior of the vacuum chamber 18 through the rows 26, 28, and 30 of perforations. This establishes a predetermined pressure differential across the copy material 12 and holds it in intimate sliding engagement with the wall 18B. This permits the heat stored in the wall 18B and in the heat sinks or sole plates associated with the electrical heating units 32 and 34 to be transmitted by conduction through these thermally conductive parts and from the back of the copy material 12 to the top or front surface on which the powder image is disposed. The use of the vacuum chest 18 producing the pressure differential across the copy material 12 removes any film of air that exists between the back surface of the copy material 12 and the wall 18B and thus provides a good overall coefficient of thermal conductivity to the thermoplastic resin forming the toner particles. These particles are thus fused to fix or place in permanent form the image carried on the front or outwardly facing surface of the copy material 12.

In one fixing or fusing unit 10 constructed in accordance with the present invention using a vacuum in the chest 18 on the order of 3-6 inches of water, a toner material that fuses in the temperature range between 70-115° C., a copy material feed rate in the range of 15-50 feet per minute, a plate 18B temperature in the range of 120-150° C., it was observed that the toner material was fully fused to the copy material 12 and that there was no evidence of discoloration of the copy material 12. The length of the wall 18B in this unit is approximately 3-5 inches, and thus the fusing unit 10 affords a very small or compact fusing unit with a relatively short path of travel during which heat is applied but which is capable of attaining substantial paper feed rates.

Although the phenomena is not completely understood, it is believed that the improved transfer of heat to the powder image achieved with the unit 10 results from the removal of any air film or boundary layer of air from the interface between the back of the copy material 12 and the adjacent surface of the wall 18B. It appears to be true that the thermal resistance R (resistance to transfer of heat from the wall 18B to the copy material 12) approaches the relationship

$$R = dx/KA$$

where dx is the thickness of the boundary layer or film of air between the copy material 12 and the thermally conductive wall 18B affording the heat source, K is a constant for thermal conductivity of air which at one atmosphere varies from .014 to .017 with air temperatures between 32° F. and 200° F., and A is the area of the copy material 12. From this relationship, it can be seen that if the thickness of the air film can be reduced to the greatest extent possible, a corresponding reduction in the thermal resistance is effected, and the efficiency of the

heat transfer from the thermally conductive wall 18B to the copy material 12 is increased.

It will be appreciated that the significant advance made in the technique of fusing powder images by conductive heat transfer is the reduction in the air layer between the heating element and the image carrying support. The description of the invention sets forth temperature ranges for the wall 18B and the softening point of the powder material comprising the images and the speeds with which the fusing can occur. The speeds of fusing may vary widely in the instant invention depending on the softening point of the thermoplastic powders, the thickness of the copy paper or material, and the temperature of the wall 18B under the influence of the air suction system that tends to decrease the air layer.

Without the benefit of exhausting the air from between the copy material and the wall 18B, the speed of fusion is greatly decreased, and the temperature at which the wall 18B must be maintained is just below the scorching point of the copy material. Thus, the fusing system without the vacuum means is insensitive to changes in the melting point of the toner and the power input to the wall 18B in the sense that it is not possible to use a lower melting point toner and obtain an accompanying reduction in the heating power input or the temperature at which the wall 18B is held. This system lacking the vacuum means thus operates in a narrow range of speed and heat level below which there is no fusion (only at very slow speeds) and above which further increases in temperature cause scorching or burning of the copy material. The system incorporating the present invention is sensitive in the sense that changes in copy feeding speeds and temperature level are related and the use of lower melting point toners permits a reduction in operating temperature or an increase in copy speed. Accordingly, the present invention results in a highly efficient system permitting both the use of low wattage inputs with high speed fusion at temperatures well below the scorch point of paper and the use of thermoplastic materials having a wide range of softening temperatures.

Although the present invention has been described with reference to a single illustrative embodiment thereof, it should be understood that numerous other modifications and embodiments can be devised by those skilled in the art that will fall within the spirit and scope of the principles of this invention.

What is claimed and desired to be secured by Letters Patent of the United States is:

1. Apparatus for fixing thermoplastic powder images carried on one surface of web or sheet material comprising:

stationary heating means for slidably receiving said sheet material thereon and applying heat by conduction to the surface opposite said image carrying surface,

transport means for slidably moving said sheet material across said stationary heating means, and means for removing the air between said heating means and the material so that said sheet or web material is held in intimate contact with said heating means as the material is transported thereacross.

2. An apparatus for fixing powder images carried on one surface of web or sheet material comprising:

an enclosure having a stationary wall portion of thermally conductive material and spaced apertures through said wall portion,

heating means for applying heat to said wall portion, an air moving means coupled to said enclosure for

moving air into said enclosure through said apertures and for withdrawing air from said enclosure, thereby to maintain a pressure differential along said wall portion,

and feeding means for feeding web or sheet material over said wall with said one surface facing away from said wall, said sheet or web material being held in intimate sliding contact with said wall by said air moving means so that heat from said heating means is transferred to said powder image by conduction through the wall and the web or sheet material as the latter is moved across said wall.

3. An apparatus for fusing powder images carried on one surface of web or sheet material comprising:

an enclosure having a stationary wall of thermally conductive material, said wall having spaced openings therein,

electrical heating means carried on an interior surface of said wall for supplying heat to said wall, feeding means for feeding web or sheet material over an outer surface of said stationary wall with said one surface of the sheet or web material facing away from said outer surface of said wall, and air moving means coupled to the enclosure for producing a pressure differential across the wall and material to hold the material in intimate sliding contact with the wall as the material is transported thereacross.

4. An apparatus for fusing toner images on one surface of web or sheet material comprising:

a vacuum chamber having a stationary material engaging structure formed of thermally conductive material, said structure having spaced openings therein, electrical heating means coupled to the structure for supplying heat to the structure, and

material feeding means for feeding said material relative to the structure, said material being held against said structure during movement by the vacuum in the chamber so that heat is transmitted by conduction through the structure and the material to the toner image.

5. The apparatus set forth in claim 4 in which the structure includes a wall having spaced lines of openings,

and the electrical heating means are carried on the wall in the areas between the spaced lines of openings.

6. The apparatus set forth in claim 5 in which the electrical heating means includes spaced and elongated heating units extending generally transverse to the direction of movement of the material relative to the structure.
